UNITED STATES PATENT OFFICE.

LEO J. GAGNON, OF DETROIT, MICHIGAN.

NONGLARE ATTACHMENT FOR HEADLIGHTS.

Application filed February 25, 1924. Serial No. 694,858.

To all whom it may concern:

Be it known that I, LEO J. GAGNON, a citizen of the United States, and resident of Detroit, in the county of Wayne and State 5 of Michigan, have invented new and useful Improvements in Nonglare Attachments for Headlights, of which the following is a specification.

This invention relates to deflectors for 10 headlights for automobiles, motor boats and the like, and has for its primary object the provision of a deflector that may be quickly attached upon the usual socket connection for the bulbs utilized in headlights and which 15 will serve to deflect the light rays that would ordinarily reach the eyes of a driver approaching the headlight.

Another object of the invention is the 20 arrangement of a non-glare reflector between the lamp and the usual parabolic reflector of the headlight that will diffuse the light rays projected from the lamp so as to utilize them in illuminating the roadway in advance and at the sides of the automobile, 25 while cutting off those rays that ordinarily produce what is termed "glare".

A further object of the invention is the 30 provision of a simple, practical, and comparatively inexpensive reflector attachment for headlights, which can be readily formed from a single sheet of metal and may be securely fastened adjacent the usual bulb to prevent rattle or accidental dislocation.

Other objects and advantages will be apparent from the following description, 35 wherein reference is made to the accompanying drawings illustrating a preferred embodiment of my invention and wherein similar reference numerals designate similar parts throughout the several views.

In the drawings:

Fig. 1 is a longitudinal sectional view through a headlight with my improved non-glare attachment in position above the bulb.

Fig. 2 is a detail sectional view showing my attachment in position below the bulb.

Fig. 3 is an end view of my attachment removed from the headlight, and

Fig. 4 is a detail sectional view taken substantially on the line 4-4 of Fig. 1.

Referring now to the drawings, the numeral 5 designates a headlight casing of any desired size and configuration in which is suitably mounted the usual parabolic reflector 6 in the center of which is secured the 55 socket 7 for the reception of the usual head-

light bulb 8. The socket 7 is provided with a pair of diametrically opposed bayonet slots 9 in which extend projecting studs 10 on the bulb, whereby the bulb will be firmly fastened in position by a direct thrust to the rear of the bayonet slots and then a slight turn. These slots 9 are utilized by me for also positioning my deflector 11. Thus, as shown in Figs. 1 and 4, a pair of rearwardly 60 projecting tabs 12 on the hub portion of the deflector fit into the forward extremities of the slots 9 to hold the deflector in its desired position, and are held in such slots by the pressure exerted on the deflector by the coil 65 spring 13 encircling the bulb 8 and engaging at its extremities against the hub portion of the deflector and the flaring rear portion of the bulb.

My improved non-glare deflector is best 70 shown in Figs. 1 and 3, and comprises a substantially semicylindrical reflecting portion 11 of metal having a polished or coated surface adapted to reflect the light rays, a hub portion 11^a adapted to encircle the bulb 8 and neck portion 11^b connecting the hub and reflector portions. Preferably my improved deflector is stamped from a single 75 sheet of aluminum or other suitable metal, and then shaped to substantially the configuration shown in Fig. 3, with the neck portion 11^b as narrow as is feasible so that very 80 little surface of the reflector 6 will be covered thereby. The hub portion 11^a is provided 85 with a pair of diametrically opposed notches 14 to permit the passage of the projecting studs 10 of the bulb 8 through the central 90 opening of the hub portion.

In practice, the coil spring 13 is slipped 95 over the bulb 8 and the bulb is inserted through the hub portion 11^a of my deflector, and is then pushed into the sockets 7 with its projecting studs 10 entering the slots 9 of the socket. Just before the bulb 8 is in its rearmost position the deflector 11 is 100 turned to bring its rearwardly projecting tabs 12 into the forward portions of the slots 9. The bulb is then pressed to its rearmost position and turned to locking position 105 in the curved portions of the slots. In so doing the coil spring 13 is compressed between the flaring portion of the bulb and the front face of the hub portion of the deflector, and the pressure of the spring in this position serves to maintain the tabs 12 110 in the slots 9 as well as to hold the hub portion of the deflector in firm engagement.

with the reflector 6. In Fig. 1 I have shown the deflector 11 in position above the bulb 8, while in Fig. 2 I have shown the deflector in position below the bulb 8. It will be apparent that to maintain such positions it is only necessary to reverse the tabs 12 in the slots 9.

With the deflector 11 in the position shown in Fig. 1, the light rays from the bulb 8 that ordinarily project through the upper half of the headlight into the eyes of persons ahead of the car will be cut off and deflected downwardly onto the road shortly in advance of the car. Also certain of the light rays that would impinge against the upper half of the reflector 6 and then be reflected forwardly and upwardly would be prevented from reaching the reflector 6, instead of being diffused over the lower half of the headlight. Sometimes it happens that the reflector 6 is so shaped or positioned that light rays impinging against the lower half of the reflector are thrown forwardly and upwardly sufficiently to cast a glare in the eyes of approaching drivers. Turning my deflector 11 to the position shown in Fig. 2 will remedy this. The light rays from the bulb 8 that would ordinarily impinge against the lower half of the reflector 6 will then be cut off by my deflector 11 and diffused over the upper half of the reflector 6, whence they are thrown forwardly and downwardly.

My improved deflector will be securely held in either position as long as desired without danger of rattle or accidental dislocation, but can be immediately removed whenever desired by simply turning the bulb in its bayonet slots and then pulling the

bulb with the deflector thereon forwardly 40 from the reflector.

While it will be apparent that the illustrated embodiment of my invention herein disclosed is well calculated to adequately fulfill the objects and advantages primarily 45 stated, it is to be understood that the invention is susceptible to variation, modification and change within the spirit and scope of the subjoined claims.

Having described my invention, I claim:— 50

1. In combination with a headlight reflector having a central socket provided with a pair of diametrically opposed bayonet slots and an electric lamp having projecting portions adapted to enter said slots, a deflector having a hub portion surrounding the lamp and provided with a pair of notches for the passage of the projecting portions of the lamp, said hub portion being also provided with a pair of rearwardly 55 projecting tabs adapted to seat in said slots, and a spring arranged to hold the deflector with its tabs positioned in the slots.

2. In combination with a headlight reflector having a central socket provided with diametrically opposed slots, a bulb secured in the socket, a deflector comprising an integral deflecting portion spaced from and adapted to partially encircle the bulb, an apertured hub portion and a neck portion 60 connecting the hub and deflecting portions; the hub having a pair of rearwardly extending tabs arranged to fit in the slots of the socket.

In witness whereof I hereunto set my 75 hand.

LEO J. GAGNON.
